UNITED STATES PATENT OFFICE.

GORDON MCKAY, OF NEWPORT, RHODE ISLAND.

NAILING-MACHINE.

SPECIFICATION forming part of Letters Patent No. 257,174, dated May 2, 1882.

Application filed December 3, 1881. (No model.)

To all whom it may concern:

Be it known that I, GORDON MCKAY, of Newport, county of Newport, State of Rhode Island, have invented an Improvement in Nailing-Machines, of which the following description, in connection with the accompanying drawings, is a specification.

My invention relates to nailing-machines for boot and shoe work, and has for its object to produce a power-actuated machine by which the driver-bar is automatically raised into position to make its stroke, and is then automatically disengaged from its actuating-power and retained there until released by the operator pressing the shoe against a tripping device next the nail-tube, which effects the release of the driving-bar and permits it to make its stroke. As the driver is released and descends the actuating-power is again automatically applied to again raise the driver-bar to its uppermost position, where it is retained as before. As herein shown, the driver-bar, acted upon by a spring to make its downward stroke and by a snail-cam to elevate it in the usual manner, is provided with toggle-jointed levers, which, when the said driver-bar is raised, are straightened to retain it thus raised until the joint of the said levers is broken. The main shaft, carrying the cam by which the driver-bar is raised, is provided with a driving-pulley, loose thereon, and a friction disk or clutch splined thereon, and a clutch-shipper is employed, controlled by mechanism connected with the driver-bar in such manner that when the said bar arrives at the end of its upward movement the said friction-disk is disengaged from the driving-pulley, which thereafter runs freely upon the main cam-shaft, which is locked by the said disk, the parts remaining in this position until the joint of the toggle-lever is broken. In this instance the end of the toggle-lever not connected with the driver-bar is mounted on a rocker-shaft provided with a cam which controls the shipping-lever, and is also provided with a tappet, properly arranged relative to the movable trip mounted on the nail-tube or nose of the machine, to be acted upon by the pressure of the article in which the nail is to be driven toward the said nose, so as to break the toggle-joint and permit the driver-bar to descend, and in so doing to again engage the friction-disk with the driving-pulley, so

that the driver-bar is again raised and retained as before.

Figure 1 is a front view of a sufficient portion of a nailing-machine to illustrate this invention; Fig. 2, a side elevation thereof; and Fig. 3 a rear elevation of a portion thereof, the friction-disk being shown in section.

The parts are shown in the drawings at the instant when the driver has completed its downward stroke. The driver-bar *a*, its actuating-spring *b*, (shown in this instance as acting thereon through the intervention of a pivoted arm, *c*.) and its actuating-cam *d*, mounted on the main shaft *e*, may be of any usual construction, the mechanism for feeding the nails to be driven not being shown, as it forms no part of the present invention.

The main cam-shaft *e* has a driving-pulley, *f*, loose thereon, and a friction-clutch box, *g*, (shown as a tapering friction-disk,) splined thereon, so that when pressed against the said pulley *f* the shaft *e* will be actuated thereby to rotate the cam *d* and elevate the driver *a* in the usual manner. The said clutch-box *g* is operated by a shipper, *h*, (shown as a bent lever,) and is provided with a notched controlling-plate, *i*, which, in co-operation with a roller, *j*, mounted on the frame-work of the machine, will retain the said clutch engaged with the pulley until in its rotation the notch is brought opposite to the said roller, when the clutch may be disengaged by the action of a spring, *k*, on the shipping-lever *h*, the clutch and shaft *e* being thus locked by the said roller and prevented from further rotation until the clutch is again engaged with the pulley *f*, the disk *i* being removed from the roller *j*, which is automatically done during the downward stroke of the driver by clutch-operating mechanism, to be hereinafter described.

A toggle-lever, *l* *l'*, connected at one end with the driver-bar *a* and at the other end with a rocker-shaft, *m*, mounted in the frame-work, is straightened in the upward movement of the said driver-bar, and will thus retain the said driver elevated until the toggle-joint is broken, the said lever constituting the driver-retaining mechanism. A clutch-operating device (shown as a cam, *n*, mounted upon the rocker-shaft *m*) is, in the movement of the said shaft caused by the toggle-lever in straightening the driver then being lifted by the cam *d*, removed from

beneath the roller h' at the end of the shipping-lever h , leaving it free to be acted upon by the spring k to disengage the clutch g from the driving-pulley f as soon as the notch of the plate i arrives at the roller j , which happens just as the driver reaches its highest position, thus disconnecting the actuating-power and locking the main shaft and driver-actuating cam d in the proper position, as shown in Fig. 1, to permit the driver-bar to descend after breaking or springing the toggle-lever.

A tappet-arm, o , mounted upon the rocker-shaft m , is provided with a pin or projection, p , which is brought by the rotation of the said shaft caused by the straightening of the levers, down upon the tripper or releasing device r , shown as having a sleeve loose upon the end of the nail-tube or nose, and projecting slightly below the bottom thereof, so that when the article to be nailed is pressed toward the nail-tube to receive the nail the tappet-arm o is raised, rotating the rocker-shaft m and lever l' connected therewith sufficiently to break the toggle-joint and permit the driver to give its blow. During the descent of the driver and consequent rotation of the rocker-shaft m the clutch-operating cam n acts upon the shipper h to automatically engage the clutch g and driving-pulley, which thus connects the driving-pulley with the shaft e , causes the latter to make a revolution sufficient to lift the driver-bar when it is retained, as described, and the clutch is again automatically disengaged and the cam-shaft disconnected from the actuating-power and locked, all automatically, so that the operator has merely to place the boot or shoe against the end of the nail-tube each time a nail is to be driven.

I do not broadly claim a loose pulley and clutch to drive the shaft one revolution; nor do I broadly claim locking the driver-bar in elevated position with its actuating-spring compressed.

I claim—

1. In a nail-driving mechanism, a driver-bar and driver and device to keep it elevated and its spring compressed, combined with a driven loose pulley, a clutch, clutch-controlling device, and a tripping device next the nail-tube, the movement of which device by the shoe as it is pressed against the nail-tube effects the disengagement of the driver-bar, in order that it may be operated by its spring, and also the engagement of the clutch or disk and driven pulley for a sufficient time to automatically lift the driver-bar and compress its spring, the clutch and pulley being automatically disengaged as soon as the driver-bar is again lifted, for the purpose substantially as described.

2. The driver-actuating shaft and driving-pulley and clutch thereon, combined with the driver and toggle-levers connected therewith, and the clutch-controlling cam operated by the said levers, substantially as described.

3. The driver-actuating shaft and clutch therefor, combined with the driver and toggle-levers connected therewith, and the clutch-controlling cam operated by the said levers, and the tappet-arm and trip therefor operated by the article being nailed to break the toggle-joint, substantially as described.

4. The clutch provided with a notched controlling-plate and its shipping-lever, combined with the clutch-controlling cam and the roller fixed upon the frame-work to co-operate with the said notched plate, substantially as described.

In testimony whereof I have signed my name to this specification in the presence of two subscribing witnesses.

GORDON MCKAY.
